Taiwanese Examination Report for Application No. 103307220 dated Mar. 12, 2015.

Primary Examiner — T. Chase Nelson(74) *Attorney, Agent, or Firm* — Lerner, David, Littenberg, Krumholz & Mentlik, LLP(57) **CLAIM**

The ornamental design for a footwear outsole, as shown and described.

DESCRIPTION

FIG. 1 is a bottom perspective view of a footwear outsole in accordance with a first embodiment of the ornamental design; FIG. 2 is a left side elevational view of the footwear outsole of the first embodiment;

FIG. 3 is a right side elevational view of the footwear outsole of the first embodiment;

FIG. 4 is a bottom plan view of the footwear outsole of the first embodiment;

FIG. 5 is a bottom perspective view of a footwear outsole in accordance with a second embodiment of the ornamental design;

FIG. 6 is a left side elevational view of the footwear outsole of the second embodiment;

FIG. 7 is a right side elevational view of the footwear outsole of the second embodiment; and,

FIG. 8 is a bottom plan view of the footwear outsole of the second embodiment.

Broken lines are environmental only and form no part of the claimed design. Broken lines adjacent shaded areas of the design represent the bounds of the claimed design and are not themselves a part of the claimed design.

1 Claim, 8 Drawing Sheets(56)
